UNITED STATES PATENT OFFICE.

WILLIAM H. WHITEHEAD AND THOMAS W. KENYON, OF PATERSON, NEW JERSEY.

FABRIC-RUBBING MACHINE.

Application filed February 15, 1923. Serial No. 619,285.

To all whom it may concern:

Be it known that we, WILLIAM H. WHITEHEAD and THOMAS W. KENYON, citizens of the United States, residing at Paterson, in the county of Passaic and State of New Jersey, have invented certain new and useful Improvements in Fabric-Rubbing Machines, of which the following is a specification.

This invention relates to machines for treating fabrics—and especially silk and other fine fabrics—after they have been woven so as to dispose or place the threads thereof with a view to remove blemishes resulting from the weaving, such as so-called "shiers," which are the effects of irregular spacing of the weft or filling threads, or "barre" marks, which are the result of the warp threads being irregularly spaced, as by the dents of the loom reed. This treatment is known as "rubbing" the fabric and the machine now used for performing it includes a pneumatic or other cushion over which the fabric is advanced while being treated and a rotated series of "rubbers" each of which consists of a set of blades arranged in rows nearly as long as the fabric is wide and the several rows radiating from a common shaft or other axial support which is parallel and extends transversely of the fabric, the acting edge of each blade being curved so that in rotating against the fabric edgewise and so impressing the cushion no corners will be presented to mark or streak the fabric. In order that every part of the fabric surface may be rubbed by the convex edges of the blades of this machine each set or series thereof has its blades offset or staggered with reference to the next set. Due to the convex form of the blade edges the rubbing is not uniform, and so the fabric is likely to have a more or less streaky appearance when the treatment is completed. Again, only one face of the fabric is treated at a time. Still again, the attendant has little facility to inspect the fabric because it is not positioned favorably to allow the light to pass therethrough and thus reveal irregularities.

According to this invention we eliminate the element corresponding to the cushion, which makes it necessary to give convexity to the curvature of the blades and which prevents the attendant from visually determining the progress and results of the work, and at the same time treat both sides of the fabric at once by utilizing a novel form of

rubbing device or rubber characterized by rubbing blades which, extending crosswise of the rubbing path, project toward and are arranged on opposite sides of the fabric (which is suitably held stretched) with each blade on one side out of registry with each blade on the other side and coacting therewith to maintain a bend in the (stretched) fabric. In the preferred form of the invention the rubber is reciprocated and the fabric also simultaneously advanced; moreover, in the preferred form the rubber is arranged to reciprocate in the up and down direction, involving the stretched part of the fabric being upright, whereby the attendant may have the benefit of light through the fabric to assist in visually determining the progress and results of the work.

In the accompanying drawings, Fig. 1 is a rear elevation of our machine; Fig. 2 is a side elevation; Fig. 3 is a view on a larger scale showing certain of the driving parts in section; and

Fig. 4 is a vertical sectional view of the rubber, showing the same in operative relation to the fabric.

The frame of the machine includes two uprights *a* connected at top and bottom by the struts *b*.

Removably arranged in brackets *c* projecting from the front of the frame is a squared shaft *d* on which may be slipped the beam *e* on which the fabric to be treated is wound. The fabric, *A*, extends from the beam *e* up over a roller *f* removably journaled in brackets *g* projecting from the rear of the frame, thence downward around a roller *h* removably arranged in brackets *i* also projecting from the rear of the frame and thence forward, under and around an expansion roller *j* removably journaled in brackets *k* projecting from the front of the frame, and then to a beam *l* which is slipped onto a squared shaft *m* supported as hereinafter stated. The expansion roller is simply present so as to distend the fabric transversely. It forms no part of the present invention. In the present form its peripheral portion is composed of two-part slats *j'* the members of which may be moved away from each other to distend the fabric and then toward each other in each rotation of the roller by any suitable means not shown herein because it is well known in the art.

The shaft m is supported at its ends in sockets n n' on the inner ends of gudgeons o' , p , q , being brackets in which the gudgeon o is journaled and r being a bracket in which the gudgeon o' is yieldable longitudinally being normally pressed inward by a spring s (by pressing the latter gudgeon o' outward the shaft m may be removed from the sockets). On the gudgeon o is fixed a sprocket-wheel t around which and a sprocket-wheel u extends a chain v . Sprocket-wheel u and a pulley w are fixed on the ends of a sleeve x which is journaled in a bracket y projecting inwardly from the frame. The belt (not shown) for driving the machine may extend around the pulley w .

In a pair of arms z projecting rearwardly from each upright is arranged a vertical guide-rod 2 . On these are adapted to reciprocate the side members or slides 3 of the rubber, 4 being horizontal bars connecting the two slides and arranged in two pairs in staggered relation to each other, one pair on the rear side and the other on the front side of the two slides. Each bar is grooved longitudinally at the inside and receives a metal blade 5 arranged in a horizontal plane. In the present case each blade extends nearly the full distance from one slide 3 to the other, so that it is adapted to rub the entire width of the fabric. The path of movement of the rubber is such that the part of the fabric which is held more or less stretched between the rollers h and f passes between the two pairs of blades 5 . The pairs of blades, projecting toward and thus arranged on opposite sides of the stretched part of the fabric, with each blade on one side out of registry with each blade on the other, coact to maintain bends in said part of the fabric as shown in Fig. 4.

The slides of the rubber have wrist-pins 6 to which are pivoted the upper ends of eccentric strap links 7 , the straps 8 of which embrace eccentrics 9 on a horizontal shaft 10 which is revoluble in brackets 11 on the uprights a' and penetrates the sleeve x . Shaft 10 may be coupled with sleeve x , so as to rotate therewith, by a clutch collar 12 splined on the shaft and adapted to have clutch engagement with the end of the sleeve, 13 being a lever fulcrumed in bracket 14 and having suitable engagement with a peripheral groove 15 in the clutch collar.

The downward movement of the rubber is cushioned by spiral springs 16 coiled about rods 2 and resting on the lower arms z .

Operation: Having arranged the fabric as specified, pulley w is caused to rotate and clutch collar 12 being in engagement with sleeve x the rubber will be reciprocated while the fabric is being advanced by being wound up on the beam l , the part of the fabric between rollers f and h being in a suitable

state of tension. The machine is preferably placed with its rear side opposite a light opening as a window, and as the work proceeds the attendant's position is at the front of the machine where, with the advantage of the light passing through the fabric, the fabric can be inspected as the work proceeds; after the fabric has been passed one or more times through the machine subject to the rubbing operation it can be passed through again for inspection without rubbing by manipulating the lever 13 so that the connection between sleeve x and shaft 10 is disestablished and hence the rubber is no longer reciprocated.

Since the blades on each side of the fabric are used in place of a cushion or the like to support the fabric against the pressure of the blades on the other side of the fabric the blades may have straight acting edges and each may extend the full width of the fabric. Thus, the streaking of the fabric which attends the use of convex-edged blades is avoided. "Shiers," or irregularities in spacing of the weft threads, and "barre" marks, or irregularities of spacing of the warp threads, are removed by the rubbing blades of the present invention because the blades work the fabric, maintaining the bends they form therein as running bends as they reciprocate, and so cause the weft and warp threads to find their proper or regular spacing, while they also loosen up the fibres and thus remove marks that are the effect of smoothing pressure having been applied in the weaving to some threads more than to others.

When the rubber moves down its movement is resisted by the springs and in this way the reciprocating motion is rendered smooth and substantially free from vibration and jar.

In order to subject the fabric to the proper tension the rotation of the beam e may be resisted in any suitable way, as by the band 17 attached at one end to one of the uprights and having its other end attached to a lever 18 fulcrumed in the upright and carrying an adjustable weight 19 .

Having thus fully described our invention, what we claim as new and desire to secure by Letters Patent is:—

1. A fabric rubbing machine including means for holding the fabric stretched and a movable rubber confined to move in substantial parallelism with the plane of the stretched part of the fabric, the rubber having rubbing blades extending crosswise of the path of movement of the rubber and projecting toward and arranged on opposite sides of the stretched part of the fabric with each blade on one side out of registry with each blade on the other side and coacting therewith to maintain a bend in said part of the fabric.

2. A fabric rubbing machine including means for holding the fabric stretched, a rubber, and means to reciprocate the rubber in substantial parallelism with the plane of the stretched part of the fabric, the rubber having rubbing blades extending crosswise of the path of movement of the rubber and projecting toward and arranged on opposite sides of the stretched part of the fabric with each blade on one side out of registry with each blade on the other side and coacting therewith to maintain a bend in said part of the fabric.
3. A fabric rubbing machine including means for holding the fabric stretched and advancing the same and a rubber having rubbing blades extending crosswise of the path of advance of the fabric and projecting toward and arranged on opposite sides of the stretched part of the fabric with each blade on one side out of registry with each blade on the other side and coacting therewith to maintain a bend in said part of the fabric.
4. A fabric rubbing machine including means for holding the fabric stretched and advancing the same, a rubber, and means to reciprocate the rubber in substantial parallelism with the plane of the stretched part and longitudinally of the advance of the fabric, the rubber having rubbing blades extending crosswise of said path and projecting toward and arranged on opposite sides of the stretched part of the fabric with each blade on one side out of registry with each blade on the other side and coacting therewith to maintain a bend in said part of the fabric.
5. A fabric rubbing machine including means for holding the fabric stretched and in an upright plane, a rubber movable up and down in engagement with the fabric, spring means to cushion each downward movement of the rubber, and means to intermittently elevate the rubber.

In testimony whereof we affix our signatures.

WILLIAM H. WHITEHEAD.
THOMAS W. KENYON.
